UNITED STATES PATENT OFFICE.

GEORGE KALKBRENNER, OF MARION, OHIO.

BOTTLE CAP.

Application filed December 26, 1919. Serial No. 347,318.

To all whom it may concern:

Be it known that GEORGE KALKBRENNER, a citizen of the United States, residing at Marion, in the county of Marion and State 5 of Ohio, has invented certain new and useful Improvements in Bottle Caps, of which the following is a specification.

This invention relates broadly to bottle caps, and has for its principal object to produce a cap of this character wherein the crimped edge thereof is of such formation as to insure a firm retention of a cap in an applied position upon the neck of a bottle, and yet to permit of the application of a cap 15 in its applied position with relative ease and facility.

Another object of the invention resides in a bottle cap wherein is provided a body portion having a depending annular wall 20 which is provided with suitable retaining crimps, and the lower edge of said wall being outwardly flared to provide a re-inforcing flange for the purpose of enhancing the resilient action of the crimped wall, and to provide said cap at its line of jointure between said flange and wall with a plurality of openings, which serve to slightly decrease the general rigidity of said flange so that the crimped wall of the cap may be sprung into 25 engagement with the head of a bottle neck with but the application of ordinary and easily accessible pressures.

It has been found in applying bottle caps of standard construction to bottles or other 30 similar receptacles that said caps are of such construction as to require an exercise of considerable force in order to spring the same into their applied positions. This force is not always accessible to the average person, and as a result, the caps are very likely to 35 be improperly applied so that the contents of the receptacles covered thereby are apt to be spoiled. However, through the principles of the present invention, ordinary 40 crimped metallic bottle caps are so formed as to lessen somewhat the rigidity of the crimped portions so that the latter may be readily sprung into engagement with the 45 necks of said receptacles, and to accomplish 50 this end in such manner that none of the fluid sealing properties of the cap will be sacrificed.

For a further understanding of the invention, reference is to be had to the following description and to the accompanying drawing, in which a bottle cap has been

shown wherein the preferred principles of the present invention are embodied. In the drawing:

Figure 1 is a top plan view of the bottle 60 cap comprising the preferred form of the invention.

Figure 2 is an edge elevation thereof.

Figure 3 is a fragmentary detailed perspective view of a portion of the cap, and 65

Figure 4 is a detail sectional view showing the modified form of a weakened crimp.

Referring more particularly to the details of the invention, use is made of a bottle cap 1. This cap is of the usual metallic 70 construction and comprises a circular body portion 2, whose circumferential edge terminates in a depending annular wall 3, the lower edge of the wall 3 terminates in the out-turned circular flange 4. As is customary, this cap is stamped from a single blank of metal, and in its process of formation the wall 3 is provided with the usual indentations 5, the formation of which leaving a plurality of ribs 6 which extend between the wall 3 and the flange 4. As is customary, the indentations 5 are designed to be forced into resilient frictional engagement with the beaded portion of a bottle neck, (not shown), and ordinarily the resiliency of said indentations is such as to firmly retain the cap in its applied or fluid sealing position upon such receptacle. 80 However, through the instrumentality of the flange 4, the general resiliency of the indentations is materially enhanced, since by the presence of the out-turned flange, it will be obvious that outward movement on the part of the indentations will be materially arrested, and that it will be necessary to exercise a considerable degree of pressure before the cap can be securely applied in connection with a bottle neck. 90

It is this element of pressure that has led to the adoption of the principles shown in 100 the present invention. Ordinary household implements and common bottle capping tools are not always sufficient to effect ease and facility in securely forcing such caps to assume their applied positions. It will be observed 105 that by the presence of the flange 4, and its peculiar position with relation to the indentations 5, that high pressures are necessary in order to spread the indentations to permit the same to grip the neck of a bottle in the 110 required manner. Large bottling concerns are of course, usually equipped with ma-

chines by means of which this capping operation may be quickly and automatically effected, but the present invention aims particularly to provide a cap adapted for general household use, and to construct the same so that by the mere manipulation of ordinary tools, said caps may be caused to assume applied positions when but ordinary hand pressure is utilized in connection with small portable forms of bottle capping devices.

In the attainment of this end, the cap 1 shown in the drawing, has the ribs 6 thereof provided with a plurality of apertures 7. As shown, these apertures are located at the line of jointure 8 existing between the wall 3 and the flange 4. By the presence of these apertures it will be apparent that when the cap is being forced downwardly upon the neck of a bottle, the indentations will be permitted to conveniently expand by the elimination of material effected by the presence of the apertures. In other words, the material surrounding and forming a part of the indentations will be crowded, as it were, toward and into said openings, so that the free and relatively unhindered expansion of the indentations may be effected, and in this manner the application of the cap to the neck of a bottle correspondingly rendered more simple. It has been found that by locating the apertures in the position stated, the best results may be attained, this being due to the fact that by being so located, said apertures are in a position to readily compensate for the displacement of material caused by the

expansion of the indentations. Further, it will be noted that the apertures do not extend to the periphery of the flange 4, and as a matter of fact are located within the confines of said flange. This construction eliminates the necessity of slitting the flange into a plurality of sections, as it has been found that when so cut, the cap has its resiliency considerably reduced. It will thus be manifest that by the provision of the openings 7, the resiliency of the indentations is maintained, and yet the expansion of the indentations may be more easily effected so as to simplify the application of the cap to the necks of bottles.

The structure disclosed in Figure 4 deviates from the preferred form by merely weakening the resiliency of the ribs 6 by forming notches 9 therein in place of the apertures 7. The principals in both forms, however, are identical.

I claim:

In a metallic bottle cap, a flat circular body portion, an annular wall depending from said body portion, said wall being provided with a multiplicity of resilient cap holding indentations, an out-turned flange integrally carried by the lower edge of said wall, ribs extending between said flange and wall, and a plurality of apertures formed in said ribs intermediate their ends and situated to lie within the outer periphery of said flange.

In testimony whereof I affix my signature.

GEORGE KALKBRENNER.
